FLANGED RUBBER INSERT FOR SHOES

Raymond Ross Ratcliff, Columbus, Ohio

Application October 26, 1931. Serial No. 571,109

1 Claim. (Cl. 36—58.5)

The invention relates to improvements in anti-slip or cushion inserts or pads for use in foot-wear primarily at the heel or counter portion thereof, to engage opposite sides of the heel of the foot to prevent slipping. The inserts are characterized as flanged discs of sponge rubber, either incorporated permanently into the shoe at the time of manufacture or subsequently applied into the shoe by the user, for the latter service, combined with a pliable holder adapted to be adhesively secured to the inside lining of the shoe, and to the insole thereof.

The invention also relates to the method of making the flanged sponge rubber discs from a vulcanized sponge rubber stock.

An object of the invention is to provide the interior of a shoe at the region of the heel or counter portion with inserts furnishing depressible and cushioning areas presenting non-slip surfaces for holding the shoe to the foot and avoid rubbing pressures of the shoe against the foot which blister or callous the skin, to give comfort to the foot and relief to a foot which is afflicted.

Further features and advantages of the invention will be more fully set forth in the description of the accompanying drawing in which:

Figure 1 is a plan view of the flanged sponge rubber disc from the face side thereof.

Figure 2 is a section on line 2—2, Figure 1, with the disc shown as applied to the lining of a shoe or flexible holder.

Figure 3 is a perspective view of a heel portion of a shoe with the improved discs applied therein.

Figure 4 illustrates a pair of discs mounted within a pliable holder as an article of manufacture for applying the pads within the used shoe.

Figure 5 is a section on line 5—5, Figure 4.

Figure 6 is a perspective view showing the pad being applied within a shoe.

The inserts, each constitutes a sponge rubber disc 1 of circular form having an offset annular margin or flange 2 extensive of one side of the body of the disc, to facilitate its attachment to the lining of a shoe or holder when not built into the shoe. The insert, in its manufacture, is cut or died out from a strip of vulcanized sponge rubber stock, and the flange formed by cutting the rubber with a revolving abrasive wheel or tool.

One method is to die out a blank from a sponge rubber sheet of a thickness corresponding to that of two discs, partially splicing the blank and flanging the two sections by cutting into the periphery of the blank with an abrasive wheel,

to a determined depth, after which the sections are separated forming a pair of inserts. The flanging may also be accomplished after the blank is split or the discs may be made from a sheet of the desired thickness of the disc by a rotative cylindrical abrasive tool fed against a face side of the material or sponge rubber sheet.

In cutting the disc from a sponge rubber stock the face side is very poriferous, furnishing a relatively soft friction surface while the rear side of the disc contains the skin or rind due to vulcanization within a mould which gives stability to the thin flange and provides a surface more suitable for cementing to the inside surfaces of the shoe. The disc with its flange as an integral unit is more yielding than if composed of layers or sections adhesively united or otherwise secured together, for the adhesive reduces the porosity at the joint.

The flanged disc manufactured as above described, provides an integral sponge rubber unit with a porous face side and a smooth surfaced rear side with no intermediate seam or film to destroy the yielding and cushioning qualities for the full thickness of the disc.

In Figure 3 the inserts or discs are shown as permanently secured in a low type woman's shoe during the process of shoe manufacture with the circular body portion of the discs engaged and projecting through apertures of corresponding diameter cut through the quarter lining 4, fully fitting the aperture with the friction face slightly above the plane or face surface of the shoe lining. A pair of discs are employed at relatively opposite sides of the medial heel seam line of the quarters and at a slight distance from the top edge of the quarters of the shoe.

The annular flange of the disc is interposed and lies between the lining and the outer quarters and is adhesively secured to the inner side of the lining quarters, the adhesion outwardly on the shoulder within the aperture.

In adapting the inserts or discs for subsequent application in new or used shoes, a pair of discs are mounted in a definitely spaced relation within a pliable holder 5 preferably of a parchment kid leather, the holder constituting a pair of rings 6 joined by a narrow neck portion 7. The discs are secured to the holder or rings in a manner substantially as heretofore described, for permanently securing the same within the shoe, the body portion being engaged and projecting through the aperture of the ring and the flange lapped upon and adhesively secured to the under or rear side of the ring.

Each ring portion is provided with a tab ex-

110

tension 8 for tucking beneath the sock lining of the shoe and adhesively securing to the upper side of the insole providing additional security against the pad becoming displaced or rising up 5 in the shoe. The pad is easily applied in the shoe and a preferable method being to first fold the holder at the neck to form a crease mark at the exact center to line with the back seam of the shoe quarters uniformly disposing the discs at 10 relative opposite sides from such seam and definitely locate the same at the proper position with respect to the heel of the foot.

A coating of vulcanizing cement is applied over the entire rear surface of the holder and 15 disc and then placed in the shoe with the tabs bent to tuck beneath the sock lining and lap upon the top surface of the inner sole. The pad is readily and easily fitted into the shoe and a pair of pads are usually merchandised with a 20 small tube of cement although it is possible to merchandise the product with its rear side coated with a remoistening adhesive. The use of a vulcanizing cement, however, produces a more durable adhesion which is not apt to loosen from 25 the heat and moisture of the foot.

In making the disc from a sponge rubber stock in which the pores are very small, a very soft velvet-like friction surface is obtained which will hold the shoe to the foot against slipping, preventing any rubbing action upon the foot or 80 stocking, avoiding injury to the foot and wear to the stocking and the yielding characteristics of the pad or disc offer considerable comfort to the foot.

Having described my invention, I claim:

A new article of manufacture for application into a shoe and upon the heel quarters thereof, comprising, a pliable fabric configurated to provide a pair of ring portions joined and disposed side by side by a neck portion and flanged sponge rubber discs respectively engaged through and filling the apertures of the rings with the flanges thereof adhesively secured to the rear side of the rings each ring having a tab extension at an angle to the neck portion to lap and be secured upon the insole of a shoe.
